UNITED STATES PATENT OFFICE.

JOHN RAPHAEL ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,115,108.

Specification of Letters Patent. Patented Oct. 27, 1914.

Application filed July 22, 1911. Serial No. 640,009.

To all whom it may concern:

Be it known that I, JOHN RAPHAEL ROGERS, a citizen of the United States, and a resident of Brooklyn, county of Kings, and State of New York, have invented a new and useful Improvement in Typographical Machines, of which the following is a specification.

My invention relates to typographical machines, and more particularly to that class thereof known to the public under the name "linotype" as illustrated for instance in United States Letters Patent to O. Mergenthaler, No. 436,532.

At the present day there are known in the art linotype machines in which three, four or more magazines, containing matrices for different styles or sizes of type, are arranged to deliver these matrices to an assembling mechanism by which they are composed in a common line for presentation to a mold, in which a slug or linotype is cast against them, the matrices being thereafter returned to their magazines to be again composed in different relations in succeeding lines. Such an assemblage is shown in several Letters Patent, and among them may be mentioned my previous Patent No. 890,303.

In the present instance, my invention relates more particularly to the distributing mechanism for such an organization, and wherein broadly the type or matrices are first separated according to fonts, and subsequently are delivered to their respective magazines, each of which is provided with an ordinary distributing mechanism of the Mergenthaler type, consisting of a longitudinally toothed bar and adjacent feed screws to advance the matrices along the same, as in U. S. Letters Patent No. 347,629. In such construction it frequently happens that a matrix falls improperly from the distributor bar or for other reasons is jammed or caught in or near the magazine entrance. If such matrix be not entirely disengaged from the conveying screws, its continued advance thereby would result in the bending, breakage or displacement of parts, and such result would similarly follow even were the matrix disengaged from the screw, unless it were also removed from the path of the subsequent matrices which are continually advanced in the regular way. To prevent the evil results attending such an accident, my present invention comprises means whereby

the entire distributing mechanism, including the screws, is automatically arrested upon its occurrence, and such automatic means are connected to all of the magazine entrances in such manner that a displaced matrix in any one of them will act thereon to effect the desired result.

In the accompanying drawing I have shown my invention as applied in preferred form, but many changes and modifications may be made therein without departing from its spirit; and generally speaking, I desire it to be understood that I do not limit myself to any specific form or embodiment except in so far as such limitations are specified in the claims.

In the accompanying drawing, Figure 1 is a perspective view of one end of the distributing mechanism of a linotype machine; Fig. 2 is an end view thereof with certain parts removed for the purpose of showing interior mechanism; Fig. 3 is a sectional view on an enlarged scale taken substantially on the line 3—3 in Figs. 2 and 4; Fig. 4 is a sectional view on an enlarged scale taken substantially on the line 4—4 in Fig. 3; Fig. 5 is a longitudinal section of the driving mechanism on an enlarged scale taken substantially on the line 5—5 in Fig. 2; and Fig. 6 is a diagrammatic view similar to Fig. 2, showing a different position of the parts.

Power is transmitted to the distributing mechanism by the belt A to the pulley A¹ mounted on the sleeve A¹⁴, which in turn is supported on the shaft or spindle A². Mounted upon the sleeve A¹⁴ and surrounding it is a second sleeve A⁷. The sleeve A⁷ is connected to the sleeve A¹⁴ by pins A¹⁵, A¹⁶, passing through the sleeve A⁷ and engaging loosely in circumferential grooves A¹⁰, A¹¹, formed in the sleeve A¹⁴, so as to permit the relative rotation of the two sleeves. The grooves A¹⁰ are of sufficient breadth to allow a certain limited amount of longitudinal movement between the two sleeves. The sleeve A⁷ is formed at one end with a projecting flange A⁸ so located and arranged as to make a frictional contact with the web of the pulley A¹, the flange being held in normal contact with the pulley by a spiral spring A⁹ located between the other end of the sleeve A⁷ and a flange at the end of the sleeve A¹⁴, thus constituting a friction clutch, all in the manner well understood in the art. The sleeve A⁷ acts to im-

part motion to the various elements of the distributing mechanism, including the conveying screws. Mounted thereon is a sprocket wheel A^5 , which meshes with the chain A^6 , which in turn engages the sprocket wheel A^8 upon the short shaft A^9 . On the shaft A^9 is mounted a pinion A^{10} constituting a part of a chain of gearing comprising a number of similar pinions A^{10} connected to the various distributing screws. This gearing is only conventionally illustrated in Fig. 2, its precise arrangement being immaterial so far as the present invention is concerned.

In the event that it becomes necessary to arrest the operation of the screws B , it is essential merely to break the frictional engagement between the flange A^3 on the sleeve A^7 and the pulley A^1 . To this end I provide the sleeve A^7 with a stop wheel G formed with side cam faces G^1 , four such faces being shown in the present instance, and each consisting of an inclined or wedge-like surface terminating in an abrupt descent. Pivottally mounted upon the frame at H^1 is an arm or lever H provided with a stop finger H^3 located in suitable position to be projected into the path of one of the cam surfaces G^1 of the stop wheel G . When this finger is thus actuated, it rides up the inclined surface and forces the wheel G and sleeve A^7 in the direction of the arrow in Fig. 5, and against the force of the spring A^4 , to the limited extent permitted by the pin connection A^{15} , which movement however is sufficient to break the contact between the flange A^3 and the pulley A^1 . The frictional engagement of the driving means is thus broken, and in addition thereto as the pin H^3 passes over the inclined surface G^1 , a wedging and locking action is effected which results in immediately stopping the rotation of the sleeve A^7 , sprocket wheel A^5 , and consequently the rotation of the screws B . The stop arm H is provided near its lower end with an abutment piece H^2 secured thereto and normally resting on the supporting piece J^2 , thus holding the stop finger H^3 in its retracted or inoperative position, as best shown in Figs. 1, 2 and 4. When the supporting piece J^2 is withdrawn, the stop arm H is permitted to drop forward and thus to project the stop finger H^3 into the path of the cam surfaces G^1 , effecting the stoppage of the mechanism in the manner previously indicated. The supporting piece J^2 is actuated by a device connected to the magazine entrances so that it will be removed from its normal position when a matrix fails to drop properly, in the manner now to be described.

The magazines (see Figs. 3 and 4) are provided with entrances D constituted by the flexible or elastic plates D^1 , rigidly mounted at one side in the entrance frame

and at the other side engaging lugs or projections on the longitudinally movable stop bar E . These longitudinally movable bars E (four such bars being shown in the drawing to correspond to the number of magazines illustrated) abut at one end against the frame J^6 , which is suitably pivoted at J^1 and provided with the upwardly extending arm J , which in turn carries the supporting piece J^2 previously referred to. In effect, the pivoted frame J^6 and arm J constitute a lever-like arrangement in such manner that the outward movement of the frame J^6 occasions the inward movement of the arm J , and thus frees the support J^2 from the abutment H^2 , and permits the arm H and stop finger H^3 to operate in the manner previously described to check the operation of the distributing screws, etc. The arm J and frame J^6 are held in normal and inoperative position by a spring J^3 and stop pin J^4 , and because of the abutment against the frame J^6 of the longitudinally movable bars E , these are similarly held in their inward or inoperative position, as shown in full lines in Figs. 3 and 4.

The matrices F are fed along the distributor rail C by the screws B in the usual manner and when they reach their appropriate channels, they drop into them from the rail, all as well understood in the art. In the event, however, of a matrix becoming displaced or jammed, or its failing to clear the distributor screws B , or its being left in such position as to offer an obstacle to the advance of other matrices, (as indicated by dotted lines in Fig. 3) the continued movement of the screws, or of a matrix advanced thereby, causes the displaced matrix to impinge against one of the elastic partition plates D^1 , which in turn by reason of its engagement with the lug on the corresponding bar E forces the latter outwardly and thus displaces the frame J^6 from its normal position, as indicated by dotted lines in Fig. 3. This results in the release of the abutment H^2 from the support J^2 , the forward projection of the stop pin H^3 , and the stoppage of the mechanism in the manner previously described. It is particularly to be noted in this connection that the frame J^6 is thus operable from any one of the magazine entrances in the event of the improper presentation of a matrix thereto, it being immaterial how many magazines are employed.

As disclosed in my application for Letters Patent, Serial No. 640,082, the distributing devices are supported in the frame M pivotally mounted at M^1 , and the channel entrances are supported in the frame N pivotally mounted at N^1 , whereby they may be respectively moved out of operative position. The arm J and frame J^6 are carried by the frame M , and the abutting bars E by the

frame N, and it therefore follows that this arrangement permits the ready breaking and restoration of the operating connections when the supporting frames M and N are moved out of or into normal position.

Having thus described my invention, its construction and mode of operation, what I claim and desire to secure by Letters Patent of the United States is as follows:

1. In a typographical machine, the combination of a plurality of magazines, a corresponding plurality of magazine entrances supported independently of the magazines, and distributor stop mechanism, the said mechanism comprising the controlling arm J, and the movable frame J^o connected thereto and to all the magazine entrances.

2. In a typographical machine, the combination of a plurality of magazines, a corresponding plurality of magazine entrances supported independently of the magazines, and distributor stop mechanism, the said mechanism comprising the stop arm H, the arm J to engage directly with and hold said stop arm in inactive position, and the movable frame J^o connected to the arm J and to all of the magazine entrances.

3. In a typographical machine, the combination of a plurality of magazines, a corresponding plurality of magazine entrances supported independently of the magazines, and distributor stop mechanism, the said mechanism comprising the pivoted stop arm H tending to fall by gravity into active position, the trip arm J to hold said stop arm in inactive position, and the movable frame J^o connected thereto and to all of the magazine entrances.

4. In a typographical machine, the combination of a plurality of magazines, separate entrances therefor, a supporting frame for said entrances mounted to move the entrances out of operative relation to the magazines, distributing mechanism, stop mechanism, and operating connections leading from all the magazine entrances thereto, the said connections being mounted in the said supporting frame; whereby the operative

connection is broken and restored according to the movement of the supporting frame.

5. In a typographical machine, the combination of a plurality of magazines, separate entrances therefor, a movable supporting frame for said entrances to carry them out of operative relation to the magazines, a corresponding plurality of distributor, a movable supporting frame for said distributor, stop mechanism mounted in part upon the distributor supporting frame, and operating connections from the individual entrances to said stop mechanism, the said connections being mounted upon the entrance supporting frame; whereby the operative connection is broken when the supporting frames are moved from normal position and is restored when they are returned thereto.

6. In a typographical machine, the combination of a plurality of magazines, a corresponding plurality of magazine entrances supported independently of the magazines, and distributor stop mechanism, the said mechanism comprising a plurality of longitudinally movable bars, one connected to each of the magazine entrances, and a movable frame actuated by any one of said bars for throwing the distributor stop mechanism into action.

7. In a typographical machine, the combination of a plurality of magazines, a corresponding plurality of magazine entrances, a common movable supporting frame for the several magazine entrances, and distributor stop mechanism, the said mechanism comprising a series of longitudinally movable bars, one connected to each of the magazine entrances, and devices operated by said bars for throwing the distributor stop mechanism into action.

In testimony whereof I hereunto set my hand this 21st day of July, 1911, in the presence of two attesting witnesses.

JOHN RAPHAEL ROGERS.
